UNITED STATES PATENT OFFICE.

MAXIMILIAN BRETH, OF NEW YORK, N. Y.

CLOTH-CUTTING MACHINE.

Application filed December 24, 1921. Serial No. 524,714.

To all whom it may concern:

Be it known that I, MAXIMILIAN BRETH, a citizen of the United States, residing at the city of New York, borough of Manhattan, in the county of New York and State of New York, have invented certain new and useful Improvements in Cloth-Cutting Machines, of which the following is a specification.

This invention relates to cloth cutting machines of the general type intended for operating upon a multiplicity of plies or layers of cloth of considerable depth, such as is the practice on the cutting tables of manufacturing establishments.

15 Among the objects of this invention is to provide a machine which for general purposes is adapted for universal cutting operations or as a substitute for the more complicated machines commonly used heretofore in the cutting of a pile of cloth following a pattern, but being particularly adapted for cutting slits or the like in a pile of cloth at such places where it is not feasible to use a cutting machine which is dependent upon the entry 20 of the cloth from an edge or the outside of the pattern. In other words this cutting machine is designed and adapted for the cutting of slits of any suitable length or form within a pattern, the beginning of the slit or 25 the entry of the pile of cloth resulting from the direct thrust through the cloth of a dagger-like blade or its equivalent.

A further object of my invention is to provide a power operated machine of a relatively simple mechanical nature and one which may be controlled with ease and precision while being operated in any desired direction and irrespective of the starting point on or along the pile of cloth.

40 A further object of the invention is to provide a cutting machine, the cutting element of which is a reciprocating blade and with which co-operates a self sharpening device which may be operated at any time 45 for the sharpening of the blade while the blade is being operated in the normal manner for cutting the cloth, so that not only may the sharpening operation be performed without loss of time of the machine, but the 50 degree of sharpening of the blade may be determined with precision according to the cutting action observed upon the particular pile of cloth under observation at the time, it being obvious that the result or effect of 55 the sharpening may be noticeable while the

cutting machine is being operated for its usual purpose.

A still further object of the invention is to provide a means, constituting a part of the mechanism, for co-ordinating the adjustment of the machine as to the depth of the cut of the blade in direct accordance with the depth of the pile of cloth.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a view of the left side of the machine, mainly in elevation, but with parts broken away to show details.

Fig. 2 is a rear elevation, parts being in section.

Fig. 3 is a horizontal section on the line 3—3 of Fig. 1.

Fig. 4 is a vertical sectional detail on the line 4—4 of Fig. 3.

Fig. 5 is a vertical section on the line 5—5 of Fig. 3.

Fig. 6 is a horizontal section on the line 6—6 of Fig. 3.

Fig. 7 is a vertical section on the line 7—7 of Fig. 3.

Referring now more specifically to the drawings, 10 indicates a base of a substantially rectangular piece of flat metal fixed upon the upper surface of a pair of spaced parallel runners 11. These runners are made preferably of strips of flat metal but having their ends upturned slightly at 11' to facilitate the movement of the machine over the work.

Fixed to and extending upward from the base 11 are two uprights or standards 12 and 13 indicated as being made of round tubular metal and each provided along its face adjacent to the opposite standard with a vertical slot 14 extending practically up to the upper end thereof. Within each standard is located a counterbalance device, shown as an expansion coil spring 15. The upper end of each standard is closed and reinforced by means of a cap 16 threaded thereto. The standard 12 is provided on its rear face with

a scale 17, and co-operating with this portion of the standard is a collar 18 having a set screw 19 for locking it upon the standard at any desired point.

5 The means for guiding or controlling the position or movement of the machine includes a handle 20 extending rearward from a frame or fork 21, the ends of which embrace and are fixed to the standards not far 10 above the base.

In a carrier 22 of any suitable construction, but indicated as of annular form, is hung or located a motor M having a horizontal forwardly extending shaft 23 journaled in bearings 24. The feed wires 25 lead to the motor from any suitable source and with which co-operates a switch 26 within convenient reach of the operator's hand on the handle 27 supported above the carrier 15 or motor by means of arms 28 and 29. The latter arm may carry a switch box 30 for the attachment of a lamp, not shown, which may be used if desired for illuminating the work. Extending laterally and downward from 20 each side of the carrier 22 is a plunger 31 slidable within the adjacent standard and whose lower end bears against the spring 15 therein. Each plunger is connected to the main portion of the carrier through a neck 25 portion 32 which slides along the slot 14 and which by contact with the cap 16 limits the upward movement of the motor and parts associated therewith. The force of the springs 15 is so designed as to substantially 30 lift and support the carrier, holding it up when the machine is not in operation, but the carrier and motor parts are adapted to be forced downward along the standards by pressure of one hand of the operator on the handle 27 so far as may be permitted by the collar 18. The springs 15 are long enough 40 so that the force thereof is substantially uniform throughout the range of movement of the plungers.

45 The cutting element is a straight blade 33 having a sharp point 34 at its lower end and a sharp forward edge 35. The blade is attached at its upper end at 36 to a slide 37 guided for reciprocating movement up and down in upper and lower guides 38 and 39 fixed to and constituting a part of the motor frame or carrier. Attached to the front portion of the motor is a hood 40 which substantially incloses all of the working parts 50 of the motor except the slide. The upper end of the slide projects through a hole 41 in the hood and is provided with an oil duct 42 which may be filled with any suitable lubricant at the upper end at 43.

60 To the motor shaft 23 is attached a crank 44 having a wrist pin 45 upon which is hung a link 46, through a ball bearing 47. The lower end of the link is connected to the slide by a pin 48 extending rearward from the 65 slide. The slide is offset at its lower end so

that the wrist pin and link connections lie in a field directly in line with the blade for the most effective thrust. Without meaning to be limited in any manner as to the scope of the invention, it may be observed that 70 this machine is best adapted for reciprocations of the slide and blade of about one inch with respect to the motor frame or carrier, but while the motor carrier is arranged for movement up and down along the standards 75 12 and 13 the reciprocations of the blade are independent of such movement along the standards.

The blade is arranged for movement along suitable guide members so as to stiffen or 80 reinforce the cutting end thereof, auxiliary to the guides 38 and 39. For this purpose I provide a pair of guide rollers 49 and 50 journaled on the opposite sides of the point portion of the blade and having direct rolling contact with the sides of the blade whereby the blade is held from lateral deflection. These rollers are journaled in corresponding brackets 49' and 50' fixed to the base but spaced slightly above the base. The roller 90 49 is provided with a flange 51 at its rear end against which the rear edge of the blade has bearing, and the other roller has a flange 52 which co-operates with a groove 53 formed in the left side of the blade. Thus 95 the blade is guided or stiffened for movement laterally in any direction but is free for vertical reciprocations.

The front or throat portion of the base 10 is notched or slotted at 54 to accommodate 100 the blade as it is operated therethrough in practice, and co-operating directly beneath this throat 54 is a presser foot 55 in the nature of a flat plate having a slot 56 registering with the throat 54. The presser foot 105 has connected to it one or more pins 57 extending upward from the base 10 and surrounding each of which is a coil spring 58 tending to force the presser foot downward as far as permitted by the head of the pin 110 or pins. This presser foot is designed to maintain the upper surface of the pile of cloth C in a smooth condition. The front portion of the presser foot has a guide rod 59 connected thereto and extended upward 115 through a guide 60 connected to the front face of the hood 40, whereby the presser foot will be held from lateral displacement, and the sharp edge of the blade guarded.

61 indicates a gage carried upon the front 120 portion of the runners 11. This gage includes a rod 62 having graduation marks thereon, the zero of which is at the left end of the rod, the graduation marks corresponding in character to those extending 125 downward along the standard 12. The rod 62 is held normally in a keeper 63 on the right hand runner, but is slideable through a guide 64 hinged at the left edge of the left hand runner whereby when the rod is de- 130

tached from the keeper 63 it may be swung upward causing the zero end of the rod to project downward below the plane of the machine. After the cloth is piled to any desired depth on the cutting table, say six inches, the machine will be lifted and placed upon the side of the pile so that the gage rod 62 as shown in the dotted line position of Fig. 5 may be projected downward until it strikes the table. The depth of the pile will then be directly readable on the rod 62 as for example in inches. The operator then brings the gage to its nested position as shown in Fig. 3 and sets the collar 18 downward along the standard 12 to a distance exactly equal to the ascertained depth of the pile of cloth, locking the collar by the screw 19 or its equivalent. I prefer also to arrange a similar scale on one side of the blade 33.

In Fig. 1 I indicate a mat comprising a sheet 65 of any suitable soft non-metallic material such as cork composition, sponge rubber, or the like, which by means of a frame 66 and base panel 66' may be slipped beneath the pile of cloth directly below the pattern or field of operation of the machine, whereby sufficient depth is provided between the lowermost ply of cloth and the surface of the table to enable the cutting blade 33 to perform its work without damage either to its own cutting edge or point or the cutting table. In other words the point of the blade may enter the mat on each downward reciprocation and thereby make a clean cut through all of the plies of cloth.

After the machine has been adjusted as above described in accordance with the depth of the pile of cloth it will be lifted into place so that the notch or throat 54 of the machine will register with the beginning of the pattern to be cut, whether it be at the side or edge of the pile or anywhere within the body thereof, and then the operator holding the handle 20 with one hand and grasping the handle 27 with his other hand will start the motor by shifting the switch 26. The blade then will reciprocate rapidly with its point directed toward the beginning of the cut as above stated. The operator then will force downward gently upon the handle 27 causing the motor to move downward, and while the motor is thus moved downward the blade will penetrate the pile of cloth to the depth limited by the position of the collar 18. Because the blade is reciprocated so rapidly and is maintained perfectly sharp such penetration of the blade is initially effected quickly. The motor and parts connected thereto may be held downward by hand if desired but I prefer to employ an automatic positive holding means for this purpose so that the operator will be relieved from the necessity

of holding the motor down while in operation, thus giving the operator the better control of the guiding of the machine over the work. The means indicated for holding the machine to its work includes a vertical rack 67 relatively close to the standard 13 and parallel thereto. This rack is journaled at its upper end in a lug 68 extending forward from the cap 16, and at its lower end in the base 10 whereby it is adapted to be moved around its vertical axis through about 90°. 70 is a bell crank lever pivoted at 71 on the fork 21, one end thereof being located adjacent to the operator's thumb of the hand on the handle 20, and having its other end projected forward past the rack having communication therewith through a link 72 and an arm 73, the latter being fixed to and extending forward from the rack. A spring 74 is attached to the lever 70 and acts normally to hold the forward end of the lever against the standard 13, whereby the rack will be held in a predetermined position. The rack has a vertical series of teeth 75 which will register with a spring pressed dog 76 extending forward from the front side of a knuckle 77 fixed to the plunger 31 by means of a pin 78 extending through the slot 14 of the standard 13 which is embraced by the knuckle. The teeth 75 are so directed downward that the dog will not engage therewith to resist the downward movement of the motor and cutting device, but by virtue of the spring 76 acting on the dog the point of the dog will engage a tooth of the rack and hold the machine down while the cutting operation progresses. When however the cutting is finished the operator has but to draw rearward on the thumb end of the lever 70 causing the front end of the lever to swing to the right as in Fig. 3 with a corresponding rotation of the rack, causing automatically the dog to be forced out of engagement with its tooth, and thus the motor and blade will be free to be lifted by the springs 15. Thus the machine will be free to be lifted at the handle 27 to another field of operation or be set aside until it is again to be used.

In the space 79 between the bearings for the rollers 49 and 50 and the base 10, are located a pair of sharpening or whetting members, such as sticks 80 of carborundum or other equivalent substances. Each of these sticks is held in a socket 81 on one side of the blade and so pivoted at 82 on the base 10 as to be caused to swing inward against the side of the cutting edge 35. The socket members are articulated together at 83, and to this point is attached at 84 a link 85 whose rear end is pivoted to the lower end of a bell crank 86 pivoted at 87 in a vertical plane beneath the fork 21. A spring 88 acts upon the link 85 to hold it urged forward,

causing the stick holders 81 to spread apart or away from the opposite sides of the blade, as shown in Fig. 3. The operator however at any time while the blade is reciprocating may, by reaching downward below the handle 20 and grasping the finger end of the bell crank 86 and pulling upward thereon, cause the link 85 to be drawn rearward, throwing the sharpening sticks 80 against the sides of the blade, one in a plane above the other, and thereby the blade will be self sharpened due to its own reciprocations. The operator may note by the behavior of the knife along its cut, according to the texture or character of the goods, when it is sufficiently sharpened and then he will release the lever 86 and permit the sharpening sticks to swing back to normal position. These sticks are so arranged as to be useful as on one face and then on each of the remaining faces of the same end by simply slipping them out of the sockets and turning them around the longitudinal axis, and after all faces of one end have been used the sticks may be turned end to end and used as many more times before they need be discarded. A leaf spring 89, as shown in Fig. 7, may be attached to each socket member 81 and have frictional bearing through a hole 90 against one face of the stick to prevent any tendency of the vibration of the machine to loosen the stick from its socket.

I claim:

1. In a cloth cutting machine, a reciprocating blade having a sharp point and a sharp edge, means to cause the blade to reciprocate at an angle to the pile of cloth, and means to control the position of the blade independent of the reciprocations, whereby the blade may be caused to be thrust through the pile of cloth at any desired point within the same remote from the edges of the pile.
2. In a cloth cutting machine, a reciprocating blade having a sharp point and a sharp edge, means to cause the blade to reciprocate at an angle to the pile of cloth, and means to control the position of the blade independent of the reciprocations, whereby the blade may be caused to be thrust through the pile of cloth at any desired point within the same and subsequently to follow a pattern while the blade continues to reciprocate.
3. A machine as set forth in claim 2 in which means is provided to guide and stiffen the otherwise free cutting end of the blade while in operation.
4. A device as set forth in claim 2 in which anti-friction rollers are arranged to co-operate with the rear and side portions of the blade to hold it from lateral movement in any direction but permit free reciprocations thereof through the pile of cloth.
5. A device as set forth in claim 2 in which

the blade is provided with a longitudinal groove along one side and anti-friction supporting means is provided for the cutting end of the blade and having a member co-acting with said groove.

6. In a cloth cutting machine, the combination with a base movable over the cloth to be cut, rigid supporting and guiding means fixed to the base and extending upward therefrom, cutting mechanism supported upon and movable as a whole up and down said supporting means and including a cutting element movable through the cloth as a result of the downward movement as aforesaid, and means under the control of the operator to control the elevation of the cutting means with respect to said supporting and guiding means.

7. A device as set forth in claim 6 in which the guiding means comprises a pair of parallel standards and the cutting mechanism movable therealong includes members co-operating respectively with said standards, resilient means acting between the standards and the cutting mechanism tending to hold the latter in a predetermined position, against the force of which the cutting mechanism may be moved by hand, and means to limit the movement of the cutting means along the standards.

8. A device as set forth in claim 6 in which the supporting and guiding means is provided with a graduated scale and a stop member adjustable therealong and the machine is provided with means for measuring accurately the depth of the cloth for determining the position of adjustment of said stop member.

9. A device as set forth in claim 6 in which the cutting means includes a reciprocating blade movable downward through the cloth beginning at any desired point in the pile of cloth toward the cutting table, and the supporting and guiding means is provided with a graduated scale and a stop member co-acting therewith, and means to preliminarily determine the depth of the pile of cloth in order to adjust the stop member according to the length of the cutting blade to be made effective beneath the base of the machine.

10. A device as set forth in claim 6 in which the supporting means comprises a pair of vertical tubular members each having a guide slot along its side toward the opposite member, while the cutting mechanism movable therealong includes a pair of plungers movable longitudinally within the tubular members and having neck portions projected through and slidable along the slots aforesaid, and spring means co-operating with the plungers for moving the same along the tubular members in one direction.

11. In a cloth cutting machine, the combination of a base, a pair of upright stand-

ards fixed thereto, a motor, a carrier for the motor guided for movement up and down along said standards, a cutting blade to reciprocate parallel to said standards, means 5 to connect the blade to the motor to cause such reciprocations, and means to control the movement up and down of the motor and carrier independently of the reciprocations of the blade.

10 12. A device as set forth in claim 11 in which the standards are tubular and each is provided with an open slot on the side adjacent to the opposite standard while the motor carrier is provided with a pair of 15 plungers projected into and slidable along the tubular members through said slots, a coil spring in each standard tending to move the carrier in one direction, means adjustable with respect to the standards according 20 to the depth of the pile of cloth being operated upon to limit the movement of the carrier along the standards, and means under the control of the operator to control the operation of the cutting member.

25 13. In a cloth cutting machine, a base movable over the cloth, upright supporting and guiding means fixed thereto, a motor, a carrier for the motor guided for movement along the supporting means, a cutting member 30 associated with the motor and operated therefrom and movable therewith as a whole toward and through the pile of cloth, means tending to hold the motor carrier in one extreme position while the carrier is moved in 35 the other direction by the hand of the operator, and means acting to resist the action of the aforesaid holding means.

14. A machine as set forth in claim 13 in which the holding means acting upon the 40 motor carrier tends to hold it elevated while the resisting means serves to hold the carrier and cutting means down to its work.

15. A device as set forth in claim 13 in which the holding means comprises a spring 45 tending to keep the cutting means elevated and positive means is provided acting to hold the cutting means down into its work

against the force of the spring means aforesaid, and means is provided under the control of the operator's hand to release said 50 positive means to allow the spring means to lift the cutting means.

16. In a cloth cutting machine, a base movable over the cloth, rigid upright means fixed to the base, a motor, cutting means carried by and actuated from the motor, a carrier for the motor supported by and movable along the upright means, means to move the carrier and motor along the upright means independently of the actuations of the cutting means, positive means to hold the carrier and motor in cutting position relative to the pile of cloth, and hand controlled means to release said positive means when the cutting operation is ended.

17. In a cloth cutting machine, the combination of a cutting member, means to actuate the cutting member to cause the same to pierce through the cloth at any desired point remote from the edges, and means to keep the cutting member sharp while in operative relation with the cloth to a degree of sharpness determined by the character or quality of the goods being cut.

18. A machine as set forth in claim 17 in which the cutting member is a reciprocating blade and the means for keeping it sharp while in action includes whetting members movable toward the opposite sides of the cutting edge coincident with the normal cutting operation of the machine.

19. A cloth cutting machine comprising a base supportable upon the top of the cloth, a blade, means to reciprocate the blade relatively to the base, a presser foot beneath the 85 base, and means to control the position of the presser foot.

20. A device as set forth in claim 25 in which the means to control the presser foot includes a guard for the sharp edge of the 90 blade.

In testimony whereof I affix my signature.

MAXIMILIAN BRETH.
